UNITED STATES PATENT OFFICE.

FRANK J. BORT, OF CLEVELAND, OHIO.

WATER-ALARM.

SPECIFICATION forming part of Letters Patent No. 339,260, dated April 6, 1886.

Application filed September 15, 1885. Serial No. 177,154. (No model.)

To all whom it may concern:

Be it known that I, FRANK J. BORT, of Cleveland, in the county of Cuyahoga and State of Ohio, have invented certain new and useful 5 Improvements in Water-Alarms; and I do hereby declare the following to be a full, clear, and exact description of the invention, such as will enable others skilled in the art to which it pertains to make and use the same.

10 My invention relates to an improved apparatus for a high and low water alarm for steam-boilers, in which two floats are employed, with a combination of lever attachments for operating the whistle-valve, to the end that high 15 or low water will operate the one or the other of the floats and sound the alarm.

In the accompanying drawings, Figure 1 is a side view in elevation of my improved apparatus in its normal position—that is, with a 20 suitable stage of water in the boiler. Fig. 2 is a side elevation showing the position of parts with high water. Fig. 3 shows the position of parts with low water.

A represents a hollow plug that is threaded 25 at *a*. This plug screws into the boiler-sheet on top of the boiler. To the upper end of the plug is attached the whistle B, that is of the ordinary construction. To the lower end of the plug and inside of the boiler is attached a 30 cross-piece, C. The cross-piece embraces the end of the plug, and is secured by a set-screw, *c*. To the cross-piece C are attached the depending arms D, E, F, and G. The arms F and G are slotted.

35 H and I are levers that pass through the slots in the arm G, and are pivoted, respectively, at *g* and *i*, as shown. The prongs of the arm F embrace loosely the levers G and I, and serve as lateral guides to these levers, and 40 the lever G is pivoted at *b*' to the valve-stem *b*. This valve is simply a rod with a conical upper end that fits a suitable seat, *b*², under the whistle, so that when the valve-stem is elevated the valve is closed and is opened by 45 depressing the valve-stem.

To the lever I is pivoted the rod I', that passes loosely through a hole in the toe *d* of the arm D, the latter serving as a guide for the rod I'. To the lower end of this rod is at- 50 tached the float I².

To the lever H is pivoted the rod G', that

passes through the toe *e* of the arm E, and to the lower end of the rod G' is attached the float G². The lever I, at the extreme of the short arm of the lever, curves upward at *i*', as 55 shown. It will be observed that the float I² is located some distance below the float G².

The arrangement of parts is such that when the water rises in the boiler to the ordinary stage suitable for carrying in the boiler the 60 float I² is elevated until the upper end of the rod I' strikes the cross-piece C, after which it can rise no farther with the water, and this elevated position of the float I² is its normal position. Now, if the water continues to rise 65 until it reaches the float G², it will have reached the upper limit that is desirable for it to rise in the boiler, and if it rises still higher it will elevate the float G² and raise the connected end of the lever G and depress the short arm of 70 the lever I, which would of course draw the valve downward and open it and sound the alarm-whistle. As the water recedes, the gravity of this float would close the valve. If, now, the water should fall so low as not to support the 75 float I², the gravity of this float would pull down the connected end of the lever I, and the point *i*' would strike the lever G and elevate it and sound the whistle. The lengths of the rods I' and G' are arranged to locate these floats, so 80 that the medium stage of water will be about midway between the floats when the float I² is raised and the float G² is depressed. It will be seen then that if the water rises or falls to any considerable extent, it will sound the whistle 85 by means of one or the other of the floats.

The device is quite inexpensive, simple, and durable.

The whistle B may be quite small, so that its 90 cost is but trifling, for the engineer is always supposed to be in the immediate vicinity and would hear the alarm if the whistle were reduced to the size of a mere toy-whistle.

The rods G' and I' are secured to the respective floats by set-screws, as shown. These rods, 95 when shipped, are of considerable length, and when the apparatus is attached to a boiler these rods are cut to suitable lengths according to the size of the boiler. Also it will be observed that the toes or guides *d* and *e* are elevated, so 100 that they are always in the steam-space, and are not therefore affected by scales that are

deposited from the water. The same may be said of all of the joints of the apparatus, and, as there is no stuffing-box for the valve-stem, there is nothing to hinder the apparatus from 5 working freely at all times.

What I claim is—

1. In a high and low water alarm, the combination, with an alarm-whistle having a valve-stem extending inwardly into the boiler, of a lever pivotally connected to said stem, a float suspended from the outer end of said lever, a second lever adapted to bear against the first-mentioned lever, and a float suspended from the second lever, all of the above parts being 15 combined substantially as set forth.

2. In a high and low water alarm, the combination, with a hollow plug secured to and extending through the walls of a steam-boiler,

a whistle attached to the outer end of said plug, the stem of the whistle-valve located inside the 20 plug and extending into the boiler, a cross-bar and arms attached to the inner end of the plug for supporting the mechanism inside of the boiler, floats connected with levers that directly or indirectly operate the valve-stem, 25 with the arrangement of levers such that the whistle-valve is opened by the elevation of one float or by the depression of the other float, substantially as set forth.

In testimony whereof I sign this specification, 30 in the presence of two witnesses, this 31st day of August, 1885.

FRANK J. BORT.
